CLAIM

The ornamental design for a set of nesting stools, as shown and described.

DESCRIPTION

FIG. 1 is a front perspective view of a set of nesting stools of three individual stools stacked and assembled with one another in accordance with this invention.

FIG. 2 is a top view of the set of nesting stools of FIG. 1. FIG. 3 is a bottom view of the set of nesting stools of FIG. 1.

FIG. 4 is a first elevational side view of the set of nesting stools of FIG. 1

FIG. 5 is a second elevational side view of the set of nesting stools of FIG. 1, taken from a direction perpendicular to the first elevational side view of FIG. 4.

FIG. 6 is an exploded perspective view of the set of nesting stools of FIG. 1 showing the three individual stools unstacked and disassembled with one another and positioned end to end.

FIG. 7 is an exploded side view of the set of nesting stools of FIG. 1 showing the three individual stools unstacked and disassembled with one another and positioned end to end; and,

FIG. 8 is an exploded top view of the set of nesting stools of FIG. 1 showing the three individual stools unstacked and disassembled with one another and positioned side by side.

1 Claim, 4 Drawing Sheets
